UNITED STATES PATENT OFFICE

2,497,000

TUYÈRE STRUCTURE

Harry O. Johnson, Donora, Pa., assignor to The
American Steel and Wire Company of New
Jersey, a corporation of New Jersey

Application March 17, 1948, Serial No. 15,311

2 Claims. (Cl. 266—41)

1

This invention relates to tuyères and more particularly to tuyères used to conduct the pre-heated air blast into a blast-furnace.

In present day blast-furnace practice, the hot blast is introduced into the furnace through tuyères which are installed in the furnace about its circumference just below the lower bosh-line. These tuyères are usually frusto-conical in shape and cast from a copper alloy or other similar material. The number of tuyères used in blast-furnaces operating today ranges from 10 to 22.

The maintenance of tuyères is an important problem in the operation of a blast-furnace and one that seriously affects iron production. The fact that tuyères must necessarily be positioned in the hearth of a furnace immediately above the molten metal and slag causes them to be subjected not only to the heat and abrasion of the blast entering the furnace but also to the intense heat given off by the molten slag and metal in the hearth. Under these conditions, the tuyères wear rapidly and burn out after being in use only a relatively short time. This necessitates frequent replacements which result in a high copper waste as well as a loss in iron production.

Many attempts have been made to solve this troublesome problem, such as reinforcing the tuyère by providing an insert of a material having a high temperature melting point in the bottom of its nose or by constructing the tuyère with an inwardly sloping nose so as to protect its bottom. Although these changes improve the situation somewhat, furnace operators still find it necessary to replace tuyères frequently during a furnace campaign.

A principal object of my invention is to provide a tuyère that will have a prolonged service life and require few replacements during a blast-furnace campaign.

Another object of my invention is to provide a tuyère that is designed to effectively withstand the deteriorating conditions that it is subject to when in use.

A further object of my invention is to provide a tuyère having surfaces adapted to receive and retain a layer of protective material thereover.

Still another object of my invention is to provide a tuyère covered with a protective refractory coating and provided with means to transfer the heat from said refractory coating to the cooled shell of the tuyère.

These and other objects will become more apparent after referring to the following specification and attached drawings, in which:

2

Figure 1 is a side elevational view of the tuyère of my invention showing its exterior surface;

Figure 2 is a nose end view of Figure 1;

Figure 3 is a longitudinal-sectional view of the tuyère taken on the line III—III of Figure 1;

Figure 4 is a cross-sectional view of the tuyère taken on the line IV—IV of Figure 3;

Figure 5 is a rear end view of the tuyère; and

Figure 6 is an enlarged detail section of the 10 tuyère nose showing the heat resistant refractory material applied.

Referring more particularly to the drawings, reference numeral 2 indicates a tuyère having the usual hot air passage 4 therethrough which 15 is surrounded by a cooling chamber 6. As shown in Figures 1 and 2, the exterior surface 8 of the tuyère has spaced-apart, longitudinal and transverse ribs 10 projecting therefrom. The inner wall 12 of air passage 4, as seen in Figures 20 3 and 4, likewise has similar longitudinal and transverse ribs 14 projecting therefrom. Longitudinal ribs 10 extend around the nose 16 of the tuyère and are continuous with the longitudinal ribs 14 projecting from the inner wall 12. A projecting rib 18 extends circumferentially around the face of the nose 16 approximately midway between the exterior surface 8 and inner wall 12.

The interior and exterior surfaces of the tuyère between the various ribs are covered with a suitable heat resistant refractory material 20, as 30 shown in Figure 6.

One of the purposes of the waffle-type surface thus formed on the exterior of the tuyère, its nose, and on the interior wall of the air passage 35 is to receive and retain the refractory material applied. To facilitate the keying of the refractory coating onto the exterior surfaces, the ribs 10 can be tapered inwardly toward their centerline, as shown. The ribs 10, 14, and 18 also serve 40 to transfer heat from the refractory 20 to the water-cooled shell of the tuyère body. The refractory coating is preferably of a thickness equal to the height of ribs 10, 14, and 18.

It will be apparent that the size and design of 45 this waffle-type pattern can vary widely but, in any case, the construction must be such as to offer reinforcement for retaining the refractory material securely to the body of the tuyère and to transfer heat from the refractory to the cooled 50 tuyère shell.

The advantage of applying refractory to the inner surface as well as the outer surface and the nose is to protect the air passage of the tuyère from destruction in case iron or cinder flows back 55 into the tuyère and also to protect the inner wall

from the heat of the hot air blast. The former is a common occurrence if the furnace is too cold, too limey, if there is a bad distribution of the stock or blast, or if, for any reason, the furnace is too full and the blast is reduced or taken off.

The waffle-type pattern of the outer and inner surfaces of the tuyère is cast directly on the surface portions of the tuyère body when the tuyère is made in the foundry.

While one embodiment of my invention has been shown and described, it will be apparent that other adaptations and modifications may be made without departing from the scope of the following claims:

I claim:

1. In a tuyère having a body portion with an air passage extending therethrough, the improvement consisting of a network of spaced-apart intersecting ribs projecting from the exterior surface of said body portion, refractory material extending between said ribs, a network of spaced-apart ribs projecting from the inner wall of said air passage, and refractory material extending between said ribs.

2. In a tuyère having a body portion with an

air passage extending therethrough, the improvement consisting of a network of spaced-apart intersecting ribs projecting from the exterior surface of said body portion, a network of spaced-apart intersecting ribs projecting from the inner wall of said air passage, said ribs forming individual compartments on the exterior surface of said body portion and on the inner wall of said air passage, and refractory material extending between said ribs to substantially fill said compartments.

HARRY O. JOHNSON.

Certificate of Correction

Patent No. 2,497,000

February 7, 1950

HARRY O. JOHNSON

It is hereby certified that error appears in the printed specification of the above numbered patent requiring correction as follows:

**Column 3, line 22, before the word "ribs" insert *intersecting*;
and that the said Letters Patent should be read with this correction therein that the same may conform to the record of the case in the Patent Office.**

Signed and sealed this 16th day of May, A. D. 1950.
